UNITED STATES PATENT OFFICE.

JAMES C. FULTON, OF ROCKPORT, TEXAS.

GOVERNOR FOR WATER-ELEVATORS.

SPECIFICATION forming part of Letters Patent No. 228,524, dated June 8, 1880.

Application filed January 12, 1880.

To all whom it may concern:

Be it known that I, JAMES C. FULTON, of Rockport, Aransas county, Texas, have invented a new and useful Improvement in Governors for Water-Elevators, of which the following is a specification, reference being had to the accompanying drawing, which represents a side elevation of my improved governing device.

10 My invention has reference more especially to a class of water-elevators, such as windmills, which are intended to elevate water into a tank and maintain it at a given level to supply the demands of use.

15 In apparatus of this kind it has been customary to use as a governor a bucket or other open vessel, (connected with the tank by a flexible tube,) which, when filled with water from the tank, drops down by its increased 20 weight and disconnects or throws out of gear the pumping or driving mechanism from which it is suspended. This device, as usually constructed and used, is subject to many disadvantages, which it is the design of my invention to remedy.

25 In the drawing herewith, A represents the tank to be filled, and B B the frame-work of the windmill or other water-elevating mechanism.

30 C is my improved governor-vessel, which is suspended by a rope, r, in the usual manner, from the mechanism designed to be controlled by the weight of water in the vessel C. Suitable guides D D are arranged to accommodate and preserve the vertical motion of 35 the governor-vessel.

The vessel C is entirely closed, excepting an aperture at the bottom, at which there is connected a flexible tube communicating with 40 the main tank A, by which means the water is allowed to flow into the vessel C and rise to the same height as in the tank, and an aperture at the top, in which is fitted an open-ended vertical tube, F, of sufficient length to 45 allow the water to rise to the level of that in the tank in any position of the governor-vessel C without overflowing.

The suspending-rope r is connected with the usual counterbalancing-weight, so that 50 when the water falls in tank A, and by consequence also in the vessel C, the latter, being

lighter, will be lifted by the counter-balance and the shifting mechanism duly operated to increase the water-supply of the tank, but when in descending the suspended vessel is 55 brought below the level of the water in the tank, which therefore escapes through the flexible tube and continues to overflow the open vessel until the latter again rises. Besides the unnecessary waste of water occurring 60 from this source, increased expense is entailed to provide and maintain a suitable wasteway to avoid the nuisance of sloppy or icy approaches to tank and machinery. In railway service the latter is often a serious 65 inconvenience. Again, an open vessel, with nothing to guide or protect it, is always subject to the disadvantage of being jostled out of place or caught in the framing-supports of the machinery, or of getting dirt in its connecting-tube, and thus interfering with its proper action.

70 My invention consists in the combination, with the operating mechanism of a water-elevator, of a closed vessel or tank operating 75 vertically upon or within guides, and provided with an open tube, in which the water may rise to the tank-level without overflowing. When the governor-valve is at its lowest position the water again rises in the tank 80 A and vessel C. The latter, by its increased weight, falls and operates to shut off or diminish the water-supply. Thus by the automatic action of the governor the supply is regulated.

Having fully described my invention, I 85 claim and desire to secure by Letters Patent—

1. The improved water-governor for windmills and other water-elevators, consisting of an otherwise closed vessel vertically operating upon guides provided with a vertical tube 90 as a provision against overflow, substantially as and for the purpose specified.

2. The suspended vessel C, provided with the vertical tube F, in combination with guides D, flexible tube E, and suspending-rope r, substantially as and for the purpose specified.

In testimony whereof I have hereunto set my hand this 19th day of December, 1879.

JAMES C. FULTON.
